CARBURETOR ICE WARNING GAUGE

John F. Carssow, Los Angeles, Calif., assignor to
Sam M. Jarvis, Glendale, Ferris I. Palmer, Bur-
bank, and Erwin Fetschke, Glendale, Calif.

Application November 28, 1941, Serial No. 420,829

4 Claims. (Cl. 261—1)

This invention relates to a device for indicating the formation of ice in fuel carburetors, and also to devices for the prevention and for the removal of ice formed in fuel carburetors.

Ice formation is one of the most important problems in carburetion in which volatile fuels are employed, such as in gasoline carburetors. This is particularly so in gasoline carburetors which may be subjected to low temperatures and pressures, as carburetors for airplane engines. The formation of ice in the carburetors and fuel passages creates one of the great hazards in the operation of such engines. The formation of ice occurs in such carburetors from one of two causes. It may result from the low temperatures to which the engine carburetor and fuel passages are subjected as a result of low atmospheric temperatures. While such low temperatures may result in icing because of the freezing of the water vapor in the air used in carburetion, it may also arise when the outside air temperatures are as high as 50° to 65° above zero. A certain percentage of the fuel entering through the carburetor jet vaporizes. The latent heat of vaporization of this fuel is abstracted from the environment which surrounds the jet, to wit, the walls of the fuel passages, thus causing a refrigeration effect which may cause a drop of 40° to 80° F. in the temperature of the air. The effect of this drop of temperature is to freeze the moisture in the air if the air temperature is in the range of 50° to 75° F. or even higher. This causes a deposition of ice as the air passes through the carburetor venturi and deposits ice on the walls and on the throttle butterfly. This ice accumulation will retard air flow and may, if left undisturbed, completely stop the air flow by choking the opening of the venturi. But even if this excessive icing is not encountered, the retardation of air flow results in a richer mixture and in an immediate loss of power.

Since ice accumulation may occur almost instantaneously due to sudden change of atmospheric conditions or changes in altitude, the pilot is without warning until he discovers by a loss in engine R. P. M., or engine roughness, or sticking throttle, that his carburetor has iced up. It has been said that this has caused many of the forced landings for which no other reason could be assigned. Ice also tends to form when the pilot is "shooting a landing." In such case, the throttle is partly closed and the manifold vacuum is high, thus increasing the refrigeration effect. Sudden icing in such case may be critical, since

a sudden loss of engine power may cause a loss of flying speed and altitude at a critical time and result in a crash.

Various expedients have been worked out to remove the ice which has been formed. These include the injection of a mixture of alcohol and glycerine which softens the deposited ice to a degree which permits the fluid stream to carry the ice out of the carburetor. Other methods include the preheating of the air to raise the temperature to a point which prevents further icing and removes deposited ice.

In either method, it is desirable to limit the amount of the treatment, since both are deleterious to engine efficiency. The mixture of glycerine and alcohol dilutes the fuel and causes a loss of engine power. Too much heat or the prolongation of the preheating of the air beyond the time necessary to remove ice is deleterious, since it causes a loss of engine power. Extreme care must be taken in the control of the proportioning device whereby the heating of the air and its mixing with cold air is controlled. Faulty operation of this control may result in destructive detonation, resulting possibly in serious damage to the power plant.

It is an object of this invention to provide an accurate warning of the formation of ice in carburetors, particularly in airplane carburetors, and in carburetors of other vehicles subject to icing conditions.

It is another object of this invention to provide a warning of the continuance of the formation of ice in such carburetors.

It is a further object of this invention to provide a carburetor ice warning gauge whereby the degree of icing may be indicated.

It is a further object of this invention to provide a de-icing system whereby an agent capable of removing ice formed in the carburetor is automatically provided responsive to the above ice warning systems.

It is a further object of this invention to provide an anti-icing system whereby upon the warning produced by this invention, conditions in the carburetor system may be automatically provided, whereby the production of ice is either minimized or prevented.

In a general sense this invention provides means which is responsive to the accumulation of ice, whereby an electric circuit is controlled to indicate the existence of ice.

In a more specific form the accumulation of ice in the venturi of the carburetor causes a de-

crease in the intensity of a beam of light which in turn causes a variation of potential or current in a photo-electric device and actuates a warning device to indicate the presence of ice. This variation of potential or current may also actuate either a pump for injection of de-icing fluid, or control of preheating of the air, or both. When the ice has been removed, the reestablishment of the intensity of the beam of light actuates the warning to indicate the removal of the ice and also, or alternatively, automatically discontinues the operation of the anti-icing and the de-icing mechanism.

Further, or alternative means, may be provided to indicate the accumulation of ice at the throttle butterfly. This means in a general sense will indicate by the degree of closing of the throttle butterfly responsive to the relative motion of the throttle lever, the presence of ice at the throttle butterfly, and also may indicate the amount of such ice. This mechanism may automatically control the input of either the de-icing fluid or of the air preheat, or both, to cause the removal of ice and to interrupt the treatment when the ice has been removed.

These and various other objects, will be better understood by reference to the drawings, in which:

Fig. 1 is a somewhat schematic arrangement of the carburetor showing the photoelectric ice warning system, and both the air preheating system and the de-icing fluid injection.

Fig. 2 shows the throttle valve ice warning system, showing open throttle free of ice.

Fig. 3 shows the same system and the throttle in partly closed condition and ice accumulation in the valve passage.

Fig. 1 shows the photoelectric element positioned in the passage between the throttle butterfly valve and the engine manifold which is not shown. This element may be placed on the other side of the throttle. The particular photoelectric device illustrated in the drawing is a selenium cell, although other photoelectric tubes may be employed in its place. The photoelectric device as shown in Fig. 1 may be positioned at any convenient place where ice may form. In Fig. 1, 1 is the carburetor bowl, 2 is the air passage within which is positioned the main jet 3. The venturi of the carburetor is shown at 4, positioned within the air passage 5 in which is also mounted the throttle valve or disc 6. Immediately beyond the throttle valve 6 is a flange 7 upon which is mounted a photoelectric device by means of the flange 8, suitably bolted together. The photoelectric element is composed of the air and fuel passage 9 in which are positioned diametrically opposed windows 12 and 13. These windows may be made of quartz, optical glass or plate glass, or clear plastics. Chamber 14 is mounted on the tubular passage 9 and in this chamber is mounted an electric bulb 15, so that the light may be transmitted through the window 12. Chamber 16 is mounted in juxtaposition with the window 13. In this chamber is mounted a photoelectric device such as a selenium cell 17. The light passes through the window 13 and illuminates the photoelectric device 17. The lamp 15 is connected by line 19 to the battery 20. The other terminal of the battery is connected by lines 21, switch 22, ballast tube 23a and line 24 to the other lamp lead 18. The selenium cell is connected by lines 25 and 26 to the microammeter 28 suitably provided with an adjustable shunt resistance 27.

The wall of the passage 9 at a position 90° from

windows 12 and 13 carries a hollow chamber separated by a thin wall 30 from the interior of the passage 9. In this chamber is mounted a resistance wire 32 suitably electrically insulated from the metal of the wall. The element is also heat insulated from all portions of the wall of the passage 9 except opposite the thin wall 30 so that element 32 is made responsive to the temperature of the fluid in 9 and is not materially affected by heat flow through the wall of 9 from other parts of the unit. The heat leakage may also be diminished by positioning the thermoelectric element 32 in the butterfly valve 6. The resistance 32 is connected by lines 33 and 34 to the Wheatstone bridge 35. Battery 20 is connected to the bridge via lines 21, 22 and 24, and ballast tube or other voltage regulating device 23—a, the other terminal being connected to the bridge through the ballast tube 23. Across the bridge is placed a galvanometer 38 connected by line 36 and 37 to the bridge.

A de-icing fluid injection nozzle 40 may be provided in the carburetor at a place somewhat below the main fuel injection jet 3. The motor-driven pump 40—a is connected to a tank containing the de-icing fluid to be injected through 40. The air passage to the carburetor is composed of the main air scoop 43 in which is positioned a baffle 44. An auxiliary air inlet 42 which may be the hot air coming from a typical installation of an intensifier system used in aircraft or from any other source of hot air, is provided as shown. The valve 45 operated by the lever 46 is so constructed as to shut off the cold air passage 43 when it is moved to its extreme position to the right or to shut off the hot air inlet when moved to its extreme position to the left. By adjusting its position to any intermediate point a proportioning of the hot and cold air may be obtained for the desired preheating of the air through 43. The commingled air is mixed and introduced through the opening 47 into the main carburetor system.

The operation of the valve 45 and the pump 40—a may be made automatic by provision of an amplifying device 81 which amplifies the photoelectric current. The solenoid coil 82 which operates against the tension spring 83 holds the circuit open until the photoelectric current drops to a low level, when the circuit is closed by the spring 83—a through the battery 20, and the solenoid 83. The solenoid armature 84 is connected to lever 46. The tension spring 86 connected to 85 is placed in desired tension by the tension screw 87 passing through the bracket 88.

By means of the manually operated switch 40—b the motor of pump 40—a may be placed in the battery circuit through the operation of the relay 83—a.

The operation of the device is as follows. The resistance wire 32, for instance copper wire, is responsive to temperature changes, so that its resistance varies with temperature. As the temperature changes the resistance of this wire, the galvanometer needle is actuated, as is a well known phenomenon in Wheatstone bridge arrangements. The ballast tube 23 functions to maintain a constant potential across the bridge. The other arms of the Wheatstone bridge may be made of wire with a low temperature resistance coefficient, as for instance, manganin wire. By the proper design of the ballast tube and the arms of the Wheatstone bridge and the galvanometer, the galvanometer may be set to record zero or balanced position (as illustrated in the drawings)

when the temperature is 32° F. As the temperature rises above 32° F. the galvanometer will move into the region indicated as "above," indicating that the temperature is above icing conditions. When the temperature drops below 32° F. the galvanometer will indicate "below," thus showing that the temperature is in a region where ice formation may be expected.

The shunt resistance 27 is adjusted so that the galvanometer indicates zero or balanced position (as illustrated on the drawings) with the light passing from the bulb 15 through the windows 12 and 13 and illuminating the photoelectric device 17. This zero adjustment compensates for any diminution in light intensity arising from accidental dirtying of the windows 12 and 13.

When the temperature drops to icing conditions, the pilot is warned by the fact that he is in a region where ice may be expected by reason of the movement of the galvanometer needle 38 to the region marked "below." When ice is formed in the passage 9 it will cover windows 12 or 13, thus cutting down the intensity of the illumination of the photoelectric device 17. The diminution in photoelectric current passing through the microammeter 28 will move the microammeter into the region marked "ice."

When this occurs the microammeter needle or the decreased flow of current in the circuit 25-26 may actuate a relay to start the pump indicated in the drawing to pump a mixture of alcohol and glycerine through the nozzle 40 into the air passage and through the venturi 4. This fluid depositing on the ice tends to make the ice mushy and the air stream will remove the ice from the passages. The removal of the ice causes a beam of greater intensity to reach photoelectric device 17, causing an increased current in the microammeter 28. The microammeter needle moves out of the icing region either to its balanced position or perhaps into the "no ice" region, if the removal of ice has also for some reason removed any accidental dirt which has deposited on the windows. The increased current would then permit the relay to operate to stop the pump and therefore stop the injection of the de-icing fluid.

The same relay may, if it is desired, also actuate the lever arm 46 to move the lever arm to a midway position between the air passages 42 and 43 to cause the injection of hot air. The actuation of the arm 46 is, as will be understood from the above description, caused by the energizing of the solenoid 83. When the photoelectric current drops to a predetermined low figure the amplified current issuing from 81 is insufficient to energize the solenoid 82 to a degree sufficient to overcome the tension of the spring 83-a. Contact 83' is pulled downward. This may also be accomplished by manually closing 83'. The circuit is thus closed through the battery 20 and solenoid 83 moves the armature to the left against the tension of the spring 86 and lights the warning light 18.

If it is also desired to cause the injection of the deicing fluid, switch 40-b is closed and the pump motor 40-a will start when the circuit is closed at 83-a.

When the ice has been removed, either by the action of the heated air or by the action of the fluid, the increased flow of current would then open the circuit at 83' due to the increased current flow through 82. The solenoid 83 will be de-energized and the spring 86 will close the hot air inlet 42. The motor 40-a of the pump will

also be stopped by the opening of the motor-battery circuit at 83'. In this way the device can act automatically to inject the de-icing fluid or to cause a preheating of the air. Instead of an automatic operation, the movement of the lever arm 46 or the starting of the pump, the de-icing fluid through jet 40 may be manually controlled when the needle 28 indicates that ice is formed.

The accumulation of ice at the butterfly 6 may also be indicated by means of the devices illustrated in Figs. 2 and 3. In Fig. 2, the butterfly valve 6 is actuated by the slotted arm 48, which in turn is actuated by means of the throttle arm 63. The lever 48 is slidably connected via pin 49 to the arm 50. Arm 50 carries a cylinder 51 into which the arm 50 is screwed. In cylinder 51 is positioned a piston 52 mounted upon a piston rod 53 which passes through a hole in the cylinder head 54. Mounted underneath the piston 52 and within the cylinder 51 is a compression spring 55. The cylinder is provided with a slot 57 through which passes a contact arm 56 connected to the piston rod 53. Upon the bracket 60 connected to the cylinder 51 is mounted a resistance coil 58 wound upon an insulation rod 59. The upper bracket 60 carries an insulation pin 60'. With the arm 56 at the top position, the insulation pin holds the contact spring 70-b away from the bolt 60-a which is thus electrically connected to ground. The other end of the spring 70-b is fixed to bolt 70-c by means of the insulating washer 70-a. The lower end of the piston 53 is connected through coupling 61 to the arm 63. Coupling 61 carries a set screw 62 and the rod 63 passes through a bracket 64 which may be any portion of the vehicle through which the throttle arm passes. The cylinder is grounded and is further connected through the bracket 60, line 70, relay coil 71, to the battery 68. The other side of the battery is grounded at 69. The meter 66 is connected through line 67 to the live side of the battery 68, and by line 65 to resistance coil 58.

The pivoted contact 73 coacting with the fixed contact point 72, is connected to the live side of the battery 68 and through line 76 to the motor 80, the other side of which is grounded at 69. The contact 75 is also connected through the line 77 to the light 18. The other side of the light is grounded at 69.

Fig. 2 shows the throttle in open position. When there is no ice present the compression spring is of such strength that the pulling of the throttle arm 63 is insufficient to compress the spring 55 and the arm 50 and arm 63 and the cylinder 51 moves as a unit to actuate the throttle butterfly.

As the contact 56 moves downwardly, the spring 70-b presses against the bolt 60-a, closing the circuit to ground. The contact 56 being in contact with the insulation 58', keeps an open circuit in 65 and 70 and therefore the contact 75 is not actuated and remains open and no current flows through the meter 66. With the contact open, the light 18 is dark and the motor 80 is not actuated. Assume, however, ice has collected on the interior of the wall 5 (see Fig. 3). The closing of the throttle moves the butterfly 6 until it contacts the ice, which would be at a position short of closed position of the butterfly. The continued movement of the throttle arm will not further close the butterfly, but will compress the spring 55. The piston is moved downward in the cylinder 51 and the contact 56 moves off from the insulated portion onto the resistance 58. This

closes the circuit through the battery and through the meter 66. The meter 66 will indicate the position of the arm 56 upon resistance 58, since the flow of current through the meter 66 will be proportional to the resistance in the circuit. This will indicate the amount of ice which has accumulated inside the wall 5. The rod 63 is always moved to the full extent of its motion, that is, until the set screw 62 contacts with the bracket 64. The closing of the circuit thus produced energizes the coil 11 and pulls the contact 75 down against the contact 72, against the resistance of tension spring 74, and moves the toggle 74 downwardly, the pivot 78 being fixed. The downward extension of the toggle will lock the contact 75 into position to close the contact and lock it in contact with 72. The closing of this contact will actuate the light 76 which will therefore be a warning of ice formation in the passage 6, and will start the motor 80. This motor 80 may be connected to the pump for pumping of the fluid through jet 48, and may also actuate the arm 46 to admit hot air, by energizing the solenoid 83, which may be constructed and operated as illustrated in connection with Fig. 1. When the ice has been removed from the walls 5, the compression spring will automatically move the cylinder downwardly, thus resulting in a relative upward movement of the contact on the resistance to diminish the resistance in the ammeter circuit and to indicate an increased flow of current. The removal of the ice may be followed on the meter 66, since as the ice is being removed and the resistance is decreasing, an increased flow of current will be shown on 66. When this flow of current is of such magnitude as to indicate that all the ice has been removed, as will occur when the contact moves onto the insulation and the circuit through the meter is broken and the meter drops to zero, the pilot may manually pull the rod 75, thus breaking the toggle. Since the circuit through the coil 11 is broken because of the positioning of the contact 56 upon the insulation 58, the coil 11 is deenergized, the spring 74 opens the contact at 72, and the light 76 will go out and the motor 80 will stop.

Upon return of the contact 56 to the upward position, the insulating pin 60' is pushed upward, thus lifting the spring 70—b to open the circuit from 70 to ground.

In order to permit of a greater surface of contact between the throttle and the ice formed as shown in Fig. 3, semi-circular wedge-shaped flanges 89 as shown in Fig. 3 are provided.

It is to be understood that the foregoing embodiments of my invention are illustrative only and various changes and modifications may be made therein within the scope of the appended claims.

I claim:

1. Means responsive to the accumulation of ice in a carburetor system comprising a means for mixing air and fuel, a fuel passage through which said commingled fuel and air passes, a photoelectric element, a source of light, means for passing said light through said fuel passage to energize said photoelectric element, an electric circuit including said photoelectric element, and means in said circuit responsive to the variation in intensity of the beam of light.
2. Means responsive to the accumulation of ice in a carburetor system comprising a means for mixing air and fuel, a fuel passage through which said commingled fuel and air passes, a mixing venturi, a throttle, a passageway beyond said venturi, a plurality of opposed windows in the walls of said passage, a light source at one of said windows, a photoelectric element at another of said opposed windows, and an indicating electric circuit including said photoelectric element.
3. A carburetor system comprising a means for mixing air and fuel, a fuel passage through which said commingled fuel and air passes, a mixing venturi, a throttle, a passageway beyond said venturi, a plurality of opposed windows in the walls of said passageway, a light source at one of said windows, a photoelectric element at another of said opposed windows, an electrical circuit including said photoelectric element, means in said electrical circuit responsive to the variations of intensity of illumination upon said photoelectric element resulting from accumulation of ice on said windows, and means responsive to said last named means for controlling the temperature of the air entering said carburetor.
4. A carburetor system comprising a means for mixing air and fuel, a fuel passage through which said commingled fuel and air passes, a mixing venturi, a throttle, a passageway beyond said venturi, a plurality of opposed windows in the walls of said passageway, a light source at one of said windows, a photoelectric element at another of said opposed windows, an electrical circuit including said photoelectric element, means in said electrical circuit responsive to the variations of intensity of illumination upon said photoelectric element resulting from accumulation of ice on said windows, means responsive to said last named means, and means for modifying the temperature of said air entering the carburetor system, including a cold air inlet, a hot air inlet, and means for proportioning the mixture of hot air and cold air, said last named means being controlled by said means responsive to the variations of intensity of illumination upon said photoelectric element.
